DESIGN FOR A SHOE PROTECTOR

Jack Karp, Brooklyn, N. Y.

Application January 15, 1945, Serial No. 117,450

Term of patent 14 years

(Cl. D7—4)

To all whom it may concern:

Be it known that I, Jack Karp, a citizen of the United States of America, residing in the Borough of Brooklyn, city of New York, county of Kings, and State of New York, have invented a new, original, and ornamental Design for a Shoe Protector, of which the following is a specification, reference being had to the accompanying drawing, forming part thereof.

I claim:

The ornamental design for a shoe protector, as shown.

JACK KARP.
